PAIR OF SPECTACLES

Richard Canavan III, South Woodstock, Conn., assignor
to American Optical Corporation, Southbridge, Mass.

Filed Feb. 10, 1975, Ser. No. 548,462

Term of patent 14 years

Int. Cl. D16—06

U.S. CL. D16—65

Published under the Second Trial Voluntary Protest
Program on Feb. 10, 1976, as document No. B548,462

FIG. 1 is a front elevational view of a pair of spectacles embodying my new design;

FIG. 2 is a top plan view thereof, the temples being broken away for convenience of illustration; and

FIG. 3 is an elevational view of one side of the pair of spectacles, the opposite side thereof being of substantially the same appearance.

I claim:

The ornamental design for a pair of spectacles, as shown and described.
